INVENTOR:

CLARENCE M. BLODGETT,

ATTORNEY

UNITED STATES PATENT OFFICE

2,362,445

FASTENER

Clarence M. Blodgett, New York, N. Y.

Application December 20, 1941, Serial No. 423,718

7 Claims. (Cl. 24—153)

This invention relates to card indexing systems and has in one of its aspects particular reference to attachments for indexing cards, although it is not thus limited.

Cards of this type have so-called black metal tabs thereon, one on each card, and one of the objects of this invention is the provision of an attachment or tab for an index card in which, with a view both to economy of structure and time consumed in the assembling operation, the sheet metal of the tab is utilized for the attaching function.

A feature of this invention is a certain perforation with its boundary or surrounding parts, the perforation being made in the sheet metal and the boundary, as herein referred to, being in the nature of prongs or pointed integral projections.

By providing prongs of quintuplet type, I have found, in practice that the perforating qualities thereof are of a superior nature, that they are secure against displacement, after assembly, and that said prongs, as fastening elements, are easily provided in the metal stock in accordance with my herein disclosed system of manufacture.

As hereinafter further referred to, the sheet metal may have different capabilities, in the individual tabs or clips, this being as to springing qualities or freedom from them, sheet metal without such qualities being ordinarily suitable.

In forming the perforation, in accordance with another object of my invention, a five sided punch on which the facets or flat surfaces extending from the point limitedly along the stem, are of a predetermined area or length. On striking the punch into the sheet metal the aforesaid five prongs are formed.

Still another object of the invention, connected with the foregoing, is the provision of a one-piece clip or tab of this nature, with which, as over former well known types, the attaching function, or assembly with the card, may be performed in a brief or reduced period of time.

Yet another feature of the invention is the manner in which the attaching prongs are driven through the card and attached thereto. The perforations in the front and back flanges or portions of the sheet metal are herein staggered, or offset, relative to each other, and in this way portions of a front flange act as an anvil, against which the points of the prongs of the back flange meet or strike, so as to be turned first outwardly and then upwardly into one face of the card material; and portions of back flange act as an anvil, in the same manner, for turning the points of the

prongs of the front flange into the card material at the opposite face thereof.

A still further advantage is secured in practice with this invention because of the comparatively reduced number of tools required both for manufacture and for assembly with the card or the like. To attach the device to the paper stock, the sheet metal flanges are merely urged, pressed or struck inwardly.

With the above indicated objects and advantages in view, as well as others, which will hereinafter appear, the invention resides in certain novel constructions and arrangements, the essential features of which are herein fully disclosed, and illustrated, in the case of structures, in the accompanying drawing, wherein:

Fig. 1 is a front elevational view of an improved clip in position on an index card member;

Fig. 2 is a back view thereof;

Fig. 3 is an edge view of the clip before assembly with a card;

Fig. 4 is an edge view of the assembled structure;

Fig. 5 is an enlarged section on the line 5—5, Fig. 2;

Fig. 6 is a bottom plan view of the showing of Fig. 5;

Fig. 7 is a further enlarged section on the line 7—7 of Fig. 1;

Fig. 8 is a face view of a modified form of clip;

Fig. 9 is an elevational view of the right hand side of Fig. 8;

Fig. 10 is a front side view of another modified form of clip;

Fig. 11 is a view of the right hand side of Fig. 10;

Fig. 12 is a front view of another modification of structure; and

Fig. 13 is a side view of the showing of Fig. 12.

Referring in detail to said drawing, the disclosed arrangement includes a sheet metal member having a front plate or flange 10 and a back plate 11, the sheet being formed with a transverse bent juncture 12. In the instant case the front plate 10 has therein an opening 13 to render visible an insert, paper slip or label 14, which may have thereon any informative indicia.

Formed in the front plate 10 are, in this embodiment of the invention, four perforations 21, 22, 23, 24, and in the back plate 11 are three perforations 31, 32, 33, which are out of registry with any of the perforations in the front plate.

These perforations are however identical, and a

description on one is equally applicable to the others.

Each perforation, as 33, or 21, is formed by striking a punch 16 into the metal sheet, so as to form five prongs 17, each also substantially alike. The prongs 17 are formed by virtue of the punch 16 having certain facets 18, these latter being also alike, as seen in Fig. 6; and likewise in Fig. 5, where the punch is shown in a partly withdrawn position after the perforating operation.

The metal clip 10—13 with the prongs 17 thereon is formed, as shown in Fig. 3, with its legs apart, and with a card 20 therebetween. The legs or plates 10, 11 are then urged, pressed or struck inwardly, this being as the parts are either vertically disposed, as seen in Figs. 3, 4, or as said parts are horizontally positioned. Pressure may be applied to the outer faces of the plates 10, 11 by any means, it being clear that when one plate, as 10, is disposed on a support, the pressure means on the opposite or upper plate 11 may then be in the form of any weight.

As the point 26 of the punch 16 engages a sheet metal plate 11, a depression is first made, then as the punch advances, cuts are made from the depression by the angles or edges between the facets 18. But when the prongs 17 are formed, on completion of a punching function, it is a feature of the arrangement that, because of said initial depression, the tip portions of said prongs are turned partly outwardly.

The arrangement then gives a very dependable and secure series of functions, this being with the entry of the prongs 11, which are of the nature of tacks, into the paperboard or cardboard 20, and with the meeting of said tips against the opposing anvil or plate portions.

This is illustrated graphically in Fig. 7, although in some places the drawings are slightly exaggerated, for clarity of disclosure. As the prongs 17 of a plate 10, at an aperture 21, reach a plate 33, said prongs are first turned outwardly, and then at least slightly backwardly to form a secure grip. In the assembled position, the prong tips of a front plate grip the rear side of an interposed card, and the prong tips of a back plate grip the opposite or front side of said card, thus making detachment of the plates from the intact card impossible.

Certain variations of structure or different embodiments of the invention are also herein disclosed, and in the device of Figs. 8 and 9 the legs 210 and 211 are substantially similar to the aforesaid clip legs, 10, 11. The legs 210, 211, with their juncture 214, are spring constructed and arranged in closed position, so that in order to receive a paperboard unit said legs may be sprung apart. Since in this embodiment the plate 210 is indented at one side, as shown, while the plate 211 is indented at the other side, a fingerpiece 36 is thereby provided on the plate 211, and a manipulating portion or fingerpiece 37 on the plate 210.

After the plates 210, 211 have been sprung apart, and with a unit to be clamped, such as a unit 20, placed between the opposed prongs, said legs are allowed to return to the closed position, after which pressure may be applied in any manner to the outer sides of said plates, to secure the assembled results, as hereinbefore described.

In Figs. 10, 11 another embodiment of this invention is illustrated, and in this latter case front

and back legs 310, 311, with a juncture 314, are provided. The clip of this embodiment has a fingerpiece 336 on one leg 310, and a manipulating part 337, on the other leg. The result obtained with, and the functioning given by the embodiment of Figs. 10, 11 are similar to those of the second embodiment, some features of these two embodiments, and of the others, being the same.

10 In the embodiment of Figs. 12, 13, apertures 21, 33 are shown, and these are identical with similar features, as already identified in other figures, these apertures having also a plurality of prongs thereat.

15 In the disclosure referred to in the immediately preceding paragraph, a paper or fibrous unit 420, is shown with plural sheets or card members, and this unit is gripped by legs 410, 411 of the clip, the legs having therein said apertures. The clip 20 may be vended as a separate article, the legs 410, 411 being spaced apart, as in Fig. 3, after which said legs may be pressed manually inwardly, by the fingers of a user, into holding relation with the members 420.

25 Variations other than those specified may be resorted to within the scope of the invention and parts of the improvements may be used without others.

I claim:

30 1. A paper clip comprising a piece of sheet metal having a medial fold line and bent thereon to provide opposite portions, each portion having therein an aperture, the apertures being out of registry, and a set of prongs projecting inwardly from the boundary edge of each aperture, the prongs of each set having their points expanded or turned outwardly.

35 2. A paper clip including a piece of sheet metal having opposite portions, the latter having a fold line therebetween, each of said portions having therein an aperture, the apertures being out of registry, and a set of prongs projecting inwardly from the boundary edge of each aperture, the prongs of each set having the main portions thereof disposed substantially at right angles to the plane of the sheet portion, said prongs having expanded or radially outwardly turned points, whereby each set may penetrate the paper being clipped, so that the points may then meet the opposite sheet portion whereby said points may then expand farther outwardly on the same plane.

40 3. In a paper clip, a flat sheet metal plate having therein a circular aperture with a set of prongs on the boundary edge of the aperture, the 45 prongs having their main parts at substantially right angles to the plate, said prongs including base portions and points, the base portions having combined dimensions which reach around said edge, and the points being extended slightly outwardly on a circular line having a greater diameter than that of the circle.

45 4. In a paper clip comprising a flat plate of rigid material with a circular aperture therein, five prongs as elements of said plate, said prongs being projected from the boundary edge of the aperture, each prong having an outwardly turned point and a base equal to one-fifth of the circumference of the circle.

50 5. A paper clip comprising a piece of resilient sheet material having two legs disposed in substantially engaging relation, there being a fold line between the legs on which the material is bent, each leg having therein an aperture with a set of prongs on the boundary edge of each aperture, said prongs having outwardly inclined

points, a fingerpiece on one leg near the fold line, and a fingerpiece on the other leg near said line, each leg having an indentation opposite the fingerpiece on the opposite leg, so that said legs may be urged apart by the fingers of a user to admit a work paper between the points of said sets.

6. A clasp fastener for a thin sheet workpiece, comprising a strip of resilient sheet metal having two adjoining legs, one of said legs having there-in a circular aperture, at least two prongs projecting inwardly from the boundary edge of the aperture, said prongs having their points substan-

tially touching the other leg, and finger-pieces on one transverse line of said legs, each leg having therein an indentation opposite the finger-piece of the other leg.

5 7. A clip fastener for a paper workpiece, comprising a strip of sheet metal having two adjoining legs, the strip being bent upon itself at an intermediate line to provide said legs, one of said legs having a circular aperture, and a set of 10 prongs projecting from the boundary edge of said aperture towards the other leg.
